UNITED STATES PATENT OFFICE

164,768

SMOKER'S OR REFRESHMENT STAND

Martin K. Fowler, Westwood, N. J.; Trina S. Fowler administratrix of said Martin K. Fowler, deceased

Application January 18, 1951, Serial No. 13,868

Term of patent 14 years

(Cl. D80—9)

To all whom it may concern:

Be it known that I, Martin K. Fowler, a citizen of the United States, and resident in the Borough of Westwood, county of Bergen, and State of New Jersey, whose post office address is 58 Harrington Avenue in said Westwood, have invented a new, original, and ornamental Design for a Smoker's or Refreshment Stand, of which the following is a specification, reference being had to the accompanying drawing, which forms a part hereof.

I claim:

The ornamental design for a smoker's or refreshment stand, as shown.

MARTIN K. FOWLER.
